UNITED STATES PATENT OFFICE

CONRAD DIEHL, OF HEROLDSBERG, GERMANY

PAD, CUSHION OR THE LIKE

Application filed March 13, 1931, Serial No. 522,361, and in Germany February 5, 1931.

This invention relates to pads, cushions and the like, such as for instance disclosed and claimed in my co-pending application for United States Patent, Serial No. 471,182 (Series of 1925) and consists in a further improvement on pads or cushions of this kind.

The pad or cushion according to my present invention consists, similarly to the pad or cushion forming part of my aforementioned co-pending application essentially of a plurality of layers of which the outer layers serve as coverings and the inner layer or layers as a filling for the pad or cushion. According to my present invention, now, the several layers of which the pad or cushion is composed are united with each other by means of a rim which is compressed along a wave-shaped line—which may be of various conformations—to fully and securely close up and fix to each other the several layers at the rim of the pad or cushion.

If the pad or cushion is made with a rim which is compressed flat along a non-undulating line as described and claimed in my aforementioned co-pending application, there will be the possibility that the compression at the rim becomes non-uniform, the degree of non-uniformity depending upon the materials used as well as upon the width of the compressed rim and the pressure which had been applied thereto during the process of compression. In consequence of this, the union or coherence of the several layers of which the pad or cushion is composed may be destroyed during use with the result that especially the coverings or outer layers become loose rendering the pad or cushion in the first place unsightly and in the second place more or less unsuitable for use.

I have found that especially the coverings or outer layers of the pad or cushion constructed according to my aforementioned application for U. S. patent become loose, if the zone of compression at the rim of the pad is only narrow, in diametrical direction of the pad, and if it had been necessary to apply very high pressures upon the rim of the pad in order to unite the several layers thereof.

Experiments have further shown that the compressed rim of the pad and therewith the union or coherence of the several layers may be essentially improved and the practical value of the pad considerably enhanced, if the pad is compressed along its rim not in a plane as described in my aforementioned co-pending application, but if the rim is compressed along a wave-shaped line which may be of various specific conformations.

Evidently, by compressing the rim of the pad according to my present invention along a wave-shaped line, the absolute length of the line along which the rim is compressed will be considerably increased, as compared with a line of compression within a plane, said increase of the absolute length of the line of compression amounting to about from 30 to 90% as compared with a line of compression in a plane, this increase of the absolute length of the line of compression depending upon the degree of undulation which according to my present invention is given to the line of compression along the rim of the pad.

When using the term "wave-shaped line of compression" or the like I desire of being understood that I wish to imply thereby every form of a line of compression which is longer than any line of compression parallel to the periphery of the pad.

The wave-shaped line of compression along the rim of the pad according to my invention may, for instance, be of zig-zag conformation, either with sharp or rounded zig-zags, or the line of compression may follow a line composed of subsequent semi-circles or the like, without departing from the principles of my present invention or sacrificing any advantages thereof.

In the accompanying drawings I have represented a pad or cushion composed of a plurality of layers, preferably of cellular material, said layers being united with each other along the rim by exerting a suitable pressure thereon along a wave-shaped line of compression which line may be of various conformation. Fig. 1 shows the new pad as being of round conformation, the several layers being united with each other along a wave-shaped

line of compression following essentially the circumference of the pad, Fig. 2 is a side-view taken on Fig. 1, while Figs. 3 to 7 show various forms of the wave-shaped line of compression along which the layers of the pad are compressed according to my present invention. Fig. 3 in particular shows a line of compression following the shape of a wave with rounded undulations, Fig. 4 a line of compression of sharp zig-zag conformation, Fig. 5 a line of compression following the shape of a wave which is composed of semi-circles, Fig. 6 a line of compression composed of waves following a rectangular zig-zag conformation and Fig. 7 another line of compression following a line composed of waves of a shape intermediate the sharp zig-zag shown in Fig. 4 and the rectangular zig-zag shown in Fig. 6.

As may be seen from Figs. 1 and 2, the compression of the several layers near the rim of the pad or cushion is carried out in such a manner that the rim of the pad is compressed within a small zone along the circumference along a line of compression which may be of any of the forms of waves shown in Figs. 3 to 7. When uniting the several layers of the pad according to my present invention by applying pressure to the rim of the pad or cushion along a line of wave-shaped conformation, evidently the length of the line of compression will be considerably increased, as compared with the line of compression following essentially a plain circular line or any line of a conformation following essentially the conformation of the rim of the pad. In addition to the considerable increase of the length of the line of compression along which according to my present invention the several layers of the pad are united with each other by pressure, there will be obtained a further advantage which consists therein that, when applying pressure to the layers in proximity to the rim along a line of compression of wave-shaped conformation, the several layers of the pad will be caused to expand during applying pressure thereto, with the result that the mechanical union or coherence between the several layers will be greatly improved owing to the fact that the portions of the several layers which are so compressed near the rim will be more firmly united by a process which may be compared with a process of felting, said process taking place at those portions of the several layers which are united with each other by pressure along a line of compression having a wave-shaped conformation. This process of felting which takes place in the present case is so effective that a separation of the several layers compressed along a line of wave shaped conformation and especially a separation of the coverings or outer layers will be avoided with a great degree of certainty, even in case of rough handling of the pad or in case of

repeated heavy bending at portions of the pad near the rim thereof.

The pad or cushion according to my present invention evidently may be of any desired form and size and the several layers of which the pad is composed may consist of any suitable material, such as for instance, of cellular material.

I claim:

1. A pad, cushion or the like consisting of layers which are united by pressure near their circumference along a line of compression of wave-shaped conformation. 15

2. A pad, cushion or the like consisting of layers which are united by pressure near their circumference along a line of compression of wave-shaped conformation, the waves of said line of compression being directed transversely to the plane of the pad or cushion. 20

3. A pad, cushion or the like consisting of layers which are united by pressure near their circumference along a line of compression of wave-shaped conformation, the line of compression being of rounded wave-shaped conformation with the waves directed transversely to the plane of the pad or cushion. 25

4. A pad, cushion or the like consisting of layers which are united by pressure near their circumference along a line of compression of wave-shaped conformation, the line of compression being of zig-zag conformation in a direction transversely to the plane of the pad or cushion. 30

5. A pad, cushion or the like consisting of layers which are united by pressure near their circumference along a line of compression of wave-shaped conformation the line of compression being of a conformation composed of semi-circles directed transversely to the plane of the pad or cushion. 35

In testimony whereof I affix my signature.

CONRAD DIEHL.
